DISPLAY CARTON

Jesse Srofe, Cincinnati, Ohio, assignor to
Venable-Brown Company, Cincinnati, Ohio, a
partnership composed of Bryant Venable and
Bruce W. Brown

Application September 22, 1930, Serial No. 483,422

7 Claims. (Cl. 206—44)

My invention relates to display cartons of the type having lids which may be extended into position displaying an advertisement, in which means may be provided for setting the carton 5 at an incline so as to reveal the contents of the carton, and in which the carton is formed from a single blank.

It is an object of my invention to provide a 10 carton in which waste of material in cutting the blank is minimized, and in which overlapped portions at the sides of the top provide a slot for receiving the lid and display material when the carton is closed. Another object in the overlapped flaps forming the top of the carton is 15 the provision of locking tabs which preferably lock in slots on the outerlying side flaps which are so constructed as to increase the frictional grip of the locking tabs so as to form firm and stiff corners. A still further object is the provision of a lid or display cover with the score 20 lines so arranged thereon that upon opening up, the display will form naturally into a panel extending in the position designated for it.

The above objects and other objects to which 25 reference will be made in the ensuing disclosure, I accomplish by that certain combination and arrangement of parts of which I have shown a preferred modification.

Referring to the drawings:—

30 Figure 1 is a plan view of the cut and scored blank forming the carton.

Figure 2 is a perspective view of the carton with the lid open prior to filling.

35 Figure 3 is a detail side elevation showing the construction of the locking tabs.

Figure 4 is a perspective view of the closed carton.

Figure 5 is a perspective view of the carton in display position.

40 Figure 6 is a side elevation of the carton with the inclining easel supports in the bottom wall of the carton holding the carton in inclined display position.

Referring first to the blank indicated in Figure 1, the bottom wall of the carton is formed by a rectangular piece A which has articulated thereto by the usual score means, the back wall B, the front wall C, and the end walls D. The end walls have slits 1 preferably of angular 50 shape as illustrated. Articulated to the sides of the back wall B are the side overlapping flaps E and F, and articulated to the sides of the front wall C are the side overlapping flaps G and H.

The front wall C has articulated thereto a 55 cut-out panel I, with extensions J which have articulated thereto the locking flaps K having tongues L which interlock, as will hereinafter be described. The lid for the box is formed with a flap M having the usual cut-out portion N in 60 which an advertising display is formed, which

is articulated to the flap M by score lines in the usual manner. The flap O is articulated to the display flap M. The end flaps D have articulated thereto locking tabs P and Q.

The bottom wall of the box has articulated cut-out flaps 2, 3, which are articulated along lines extending laterally across the box, and tongues 4, 5, are also articulated to the bottom A so that when the easel flaps 2, 3, are opened out, the locking tongues 4 and 5 may be bent over so as to frictionally retain the easel supports so that the carton may be held in inclined display position as indicated in Figure 6.

In setting up the carton, the sides of the back and front walls B and C respectively, are folded up to a position at right angles to the bottom A. The side overlapping flaps G, E, and F, H, are then folded in to a position at right angles both to the bottom wall A and in a different plane to the front and back walls C and B. The end flaps D are then folded up into alignment with the overlapped flaps G, E, and H, F, and the tabs P, Q, are folded over to hold the three-ply ends of the box in position. The top panel I is then folded over towards a position at right angles to the end walls, and shortly before the panel M reaches this position at right angles to the side walls the tips of the tongues L are inserted 75 within the angular slots 1 in the end walls D.

Referring to Figure 3 it will be noted that the 90 tongues have cam-shaped upper edges, as indicated at 6, so that they tend to become knurled and bent over during the completion of the inserting movement within the slots I. This pulls the extensions J down tight against the tabs P and because of the knurling and roughening of the upper edges of the locking tongues, the box 95 does not tend to open up, but is held in frictionally locked rigid and stiff position.

The box is then ready for filling, and after the 100 contents have been inserted, the cover flap composed of the parts M and N, is bent to about a right angle. This bending is facilitated by providing a secondary score line 7, 7, in which the score is so formed that the top panel tends to bend naturally back to an inclined position. From this open position the tab O is slipped underneath the slit formed between the extensions J and the tabs Q. The cover panel when completely folded in is held tightly in position by the 105 frictional grip between the under surface of the extensions J and the upper surface of the tabs Q.

When it is desired to dispense the contents, the portion of the cover which is interlocked under the extensions J is withdrawn. The tab O which 115 is formed by a score line 8, 8, also applied from the outer surface of the cover, is bent at about a right angle to the flap N, and when the tab O is inserted in the space 8 between the back wall B and the end of the tabs Q, the display panel N is 120

held in a position substantially parallel with the top panel of the box in the position illustrated in Figure 6.

In bending up the display lid, the secondary score permits folding in to proper display position entirely naturally because of the arrangement of the score lines, so that an inexperienced person will naturally open out the display without requiring instructions as to the proper manner of doing so.

The combination of the members M, N and O forming the cover for the box, is not of sufficient width to extend clear across the box. This is unnecessary and would be objectionable because if the cover were as long or longer than the distance across the box from back to front, when the cover was closed the end of the tab O would strike the inner surface of the front panel C and cause a buckling of the cover. The construction illustrated allows for considerable saving in carton material required because of the short cover.

While I have only shown one preferred form of my invention, in which the cover panel need not be long enough to extend clear across the box because of the engagement within the slits between the under surface of the extensions J and the upper surface of the tabs Q, other modifications in the size and shape of parts in which a similar principle is involved, I consider within the scope of my invention.

The easel is so arranged that most of the weight of the contents is thrown on the bottom edge of the carton where it is supported across its entire front flat on the counter. The position and size of the easel may be varied according to the size, shape, and contents of the box.

Having thus described my invention, what I claim as new and desire to secure by Letters Patent, is:—

40 1. A display carton having a short display lid of insufficient dimensions to cover the space across the carton, said carton having a front panel with extensions thereof and end walls having tabs articulate thereto, said front panel extensions adapted to lie on top of the top tabs of the side walls and form laterally spaced inwardly opening slots for receiving the lateral edges of said lid with the display surface of the lid exposed between said extensions.

50 2. A display carton having a short display lid of insufficient dimensions to cover the space across the carton, said carton having a front panel with extensions thereof and end walls having tabs articulate thereto, said front panel extensions adapted to lie on top of the top tabs of the side walls and form laterally spaced inwardly opening slots for receiving the lateral edges of said lid with the display surface of the lid exposed between said extensions, and said extensions being provided with articulated flaps to extend down along the end walls of the carton and having a locking tongue engagement therewith.

3. A display carton having a short display lid of insufficient dimensions to cover the space across the carton, said carton having a front panel with extensions thereof and end walls having tabs articulate thereto, said front panel extensions adapted to lie on top of the top tabs of the side walls and form laterally spaced inwardly opening slots for receiving the lateral edges of said lid with the display surface of the lid ex-

posed between said extensions, and said extensions being provided with locking means for retaining same in closed position, comprising slits in said end walls and articulated flaps on said extensions having tongues, the upper edges of which are cam-shaped so as to lock tightly by insertion of the tongues within the slits.

4. A display carton comprising end walls with tabs extending inward along their tops, a front wall with tabs extending from its upper corners backward over and along the respective end wall tabs and secured down thereover by their laterally outer edges, with freely separable directly opposed surfaces to admit between said surfaces, at their inner edges, the opposite edge portions of a cover for the carton with the top of the cover displayed between said front wall tabs.

5. A display carton comprising a front wall, end walls and a rear wall secured in upright position, said end walls having tabs extending inward along their tops and said front wall having tabs extending from its upper corners backward over and along the respective end wall tabs and secured down thereover by their laterally outer edges, with freely separable directly opposed surfaces, and a cover hinged to the top edge of said rear wall and having its opposite edges slideable between said tabs with the top of the cover displayed between said front wall tabs.

6. A display carton comprising front, rear and end walls and a cover having a hinge connection with the top of the rear wall and being folded upon itself to display its top front surface forwardly when the cover is raised, said end walls having tabs extending inward along their tops and said front wall having tabs extending backward from its upper corners over and along the respective end wall tabs and secured down thereover by their outer edges, said front wall also having an intermediate backwardly extending tab along its top edge with its ends joining the corner tabs, and said cover, when lowered in straight condition, having edge portions held over the end wall tabs and under the front wall tabs with its front top display surface framed by said front wall tabs.

7. A display carton comprising front, rear and end walls and a cover having a hinge connection with the top of the rear wall and having its front edge portion bent down, and being folded upon itself substantially midway between said hinge connection and the bend of said front edge portion, to display its front top surface forwardly when the cover is raised, said end walls having tabs extending inward along their tops with rear ends adjacent to said rear wall, said bent down front edge portion of the cover entering between said rear ends and said rear wall to hold the cover in rearwardly inclined raised position, and said front wall having tabs extending backward from its upper corners over and along the respective end wall tabs and secured down thereover by their outer edges, and also having an intermediate backwardly extending tab along its top edge with ends joining the corner tabs, and said cover, when lowered in straight condition, having edge portions held over the end wall tabs and under the front wall tabs with its front display surface framed by the front wall tabs.
